UNITED STATES PATENT OFFICE.

RAYMOND T. BELL AND LOUIS MANDEL, OF CHICAGO, ILLINOIS, ASSIGNEES, BY
MESNE ASSIGNMENTS, TO BEN F. GOLDSTEIN, OF CHICAGO, ILLINOIS.

LID-SUPPORTER.

1,359,953.

Specification of Letters Patent. Patented Nov. 23, 1920.

Application filed December 20, 1919. Serial No. 346,340.

To all whom it may concern:

Be it known that we, RAYMOND T. BELL and LOUIS MANDEL, citizens of the United States, residing at Chicago, in the county of Cook and State of Illinois, have invented 5 certain new and useful Improvements in Lid-Supporters, of which the following is a specification.

This invention relates to improvements in 10 lid supporters particularly adapted, though not necessarily limited in its use with the lids of sound reproducing machines, and one of the objects of the invention is to provide an improved device of this character which 15 will be of a unitary structure whereby the parts may be all mounted upon the same base and whereby the device may be readily installed and at the same time insure the proper positioning of the parts with relation to each other.

A further object is to provide an improved 20 device of this character having means whereby a predetermined degree of friction may be provided between the parts for maintaining them under normal conditions in their 25 adjusted positions with respect to each other but which will, under abnormal conditions, yield to pressure or force to allow the lid to be shifted.

30 A further object is to provide improved means whereby the friction between the parts may be varied at will.

To the attainment of these ends and the 35 accomplishment of other new and useful objects as will appear, the invention consists in the features of novelty in substantially the construction, combination and arrangement of the several parts hereinafter more fully described and claimed and shown 40 in the accompanying drawings illustrating this invention, and in which:

Figure 1 is a vertical sectional view of a portion of a cabinet having a lid supporter applied thereto and constructed in accordance with the principles of this invention.

Fig. 2 is an enlarged detail view of one of the joints of the lid supporter showing the friction creating surface.

Fig. 3 is an enlarged detail sectional view 50 with parts omitted of one end of the base member.

Fig. 4 is a side elevation of Fig. 3.

Fig. 5 is an end elevation of the parts shown in Fig. 2.

55 Fig. 6 is a modification of the form shown in Fig. 2.

Fig. 7 is a view similar to Fig. 1 of another form of the invention.

Fig. 8 is an enlarged detail view of one of the joints of the lid supporter showing 60 the friction producing means.

Fig. 9 is an end elevation of Fig. 8.

Referring more particularly to the drawings the numeral 10 designates generally a casing or cabinet provided with a lid 11 65 hinged thereto in the usual manner as at 12. Secured to the wall 13 of the cabinet is a base member 14 which may be of any desired size and configuration but is preferably of a bar-like construction of considerable length having 70 openings 15 therethrough and through which openings suitable fastening devices pass to engage the casing wall and thereby anchor the base. Pivotedly connected with the base 14 as at 16 is an element 17 and to 75 the end of which element 17 is connected a link 18 as at 19. The other end of the link 18 is pivotally connected as at 20 in any suitable manner to the lid 11 so that as the lid is moved about its hinge or pivot 12 the link 80 18 will cause a pivotal movement of the element 17 about this pivot 16 and with respect to the base 14. In order to counterbalance the lid there is provided a spring 21, one end of which is suitably anchored to the 85 base 14 preferably by means of an ear 22 projecting laterally from the base and at a distance from the pivot 16. The other end of the spring 21 is detachably secured to the element 17 and in order to vary the tension 90 of the spring its end is adjustably connected with the element 17 through the medium of the openings 23 so that the ends of the spring may be detached from the element 17 and its end inserted in any desired one of 95 the openings 23.

In order to produce a friction between the base 14 and the element 17 so as to retain the lid 11 in its adjusted position friction creating means are provided. In the form 100 of the invention shown in Figs. 1 to 5 this friction creating means embodies a surface or segment 24 adjacent and encompassing the pivot 16 and which surface 24 is connected with the base member 14. The element 17 is provided with an end 25 which projects beyond the pivot 16 and over the surface 24 and carried by this end 25 is a lug or projection 26 formed in any suitable manner, preferably by stamping out a portion of 105 the end 25, and this lug 26 is adapted to enter openings 27 in the surface 24, the spring 110

or elasticity of the end 25 of the element 17 serving as a means for causing the projection to enter the opening. The projection 26 and openings 27 are of such a size and 5 configuration with respect to each other that when the projection enters one of the openings it will, under normal conditions, hold the lid in its adjusted position but, under abnormal conditions or when force or pressure is exerted upon the lid, the projections 10 will move out of one of the openings 27 and into the next opening as the element 17 is swung about its pivot.

In the form of the invention shown in 15 Fig. 6 the projection 26 is omitted as are also the openings 27 and the friction is produced by the contact of the face of the end 25 of the element 17 moving over the surface 24.

In the form of the invention shown in 20 Figs. 7 to 9, the friction creating surface adjacent the pivotal connection between the base 14 and the element 28 is formed by spaced friction disks or surfaces 29—30 which may be constructed of any suitable 25 friction creating material. In this form of the invention the base member 14 is offset as at 31 and the element 28 is pivotally connected thereto by means of a bolt or pin 32 passing through the portion 31 and the element 30 28, the bolt being provided with a head 33 engaging within the recess formed by the offset portion 31 and which bolt extends for any desired distance beyond the elements 28—29—30. The end of the bolt is provided 35 with threads 34 to receive the nut 35 and also a lock nut 36 if desired. Encompassing the bolt 32 is a spring 37 one end of which bears against one of the friction producing elements 30 and the other end bears 40 against a washer 38 which abuts the nut 35. It will thus be seen that when it is desired to vary the friction of the elements 29—30 on the element 28, all that is necessary is to tighten or loosen the nuts 35—36. 45 With this improved construction it will be manifest that there is provided a lid supporter which is of a unitary structure in that all of the parts including the friction creating means and the counterbalancing tension 50 means are mounted upon the same supporting structure and the entire device may be applied or removed as a unit. Heretofore considerable difficulty has been experienced in that the parts have been made separate or 55 detached from each other and each is secured to the wall of the cabinet thereby necessitating guessing at the proper position for the parts with respect to each other. In the present invention it will be noted that 60 the parts will be in the same relative positions with respect to each other no matter in what position they may be placed in the cabinet or the style of the cabinet.

While the preferred form of the invention 65 has been herein shown and described, it is

to be understood that various changes may be made in the details of construction and in the combination and arrangement of the several parts within the scope of the claims without departing from the spirit of this 70 invention.

What is claimed as new is:—

1. A lid supporter embodying a base element adapted to be secured to a fixed support, an element pivotally connected with 75 the base, a link pivotally connected at one end with said element, means pivotally connecting the other end of the link with the lid whereby when the lid is moved the said element and link will be moved about their pivots, means interposed between the said element and base for counterbalancing the lid, and means adjacent the pivot of the base and the said element for creating a friction 80 between these parts. 85

2. A lid supporter embodying a base element adapted to be secured to a fixed support, an element pivotally connected with the base, a link pivotally connected at one end with said element, means pivotally connecting the other end of the link with the lid whereby when the lid is moved the said element and link will be moved about their pivots, means interposed between the said element and base for counterbalancing the 95 lid, the last recited means embodying a spring detachably and adjustably connected with one of the parts for varying the stress of the spring, and means for creating a friction between one of the movable parts and 100 the adjacent co-operating member.

3. A lid supporter embodying a base element adapted to be secured to a fixed support, an element pivotally connected with the base, a link pivotally connected at one 105 end with said element, means pivotally connecting the other end of the link with the lid whereby when the lid is moved the said element and link will be moved about their pivots, means interposed between the said element and base for counterbalancing the lid, and means adjacent the pivot of the base and the said element for creating a friction 110 between these parts, the last recited means embodying an extended friction creating 115 surface over which said element moves.

4. A lid supporter embodying a base element adapted to be secured to a fixed support, an element pivotally connected with the base, a link pivotally connected at one 120 end with said element, means pivotally connecting the other end of the link with the lid whereby when the lid is moved the said element and link will be moved about their pivots, means interposed between the said element and base for counterbalancing the lid, means adjacent the pivot of the base and the said element for creating a friction 125 between these parts, the last recited means embodying an extended friction creating sur- 130

face over which said element moves, and means whereby the degree of friction may be varied.

5. A lid supporter embodying a base element adapted to be secured to a fixed support, an element pivotally connected with the base, a link pivotally connected at one end with said element, means pivotally connecting the other end of the link with the lid whereby when the lid is moved the said element and link will be moved about their pivots, means interposed between the said element and base for counterbalancing the lid, and means adjacent the pivot of the base 10 and the said element for creating a friction between these parts, the last recited means embodying an extended friction creating surface adjacent and encompassing the pivot between the base and said element and over 15 which surface the element moves.

6. A lid supporter embodying a base adapted to be secured to a fixed support, an element pivotally connected with the base, a link pivotally connected by one end with 25 the said element and by its other end to the lid whereby when the lid is moved the parts will be moved about their pivots, a spring connected at one end with the said element and anchored by its other end to the said 30 base, a friction element adjacent the pivot of the said element and the base for creating a friction between the last two recited parts, and means operating upon the said friction element for maintaining it active.

35 7. A lid supporter embodying a base adapted to be secured to a fixed support, an element pivotally connected with the base, a link pivotally connected by one end with the said element and by its other end to the lid whereby when the lid is moved the parts 40 will be moved about their pivots, a spring connected at one end with the said element and anchored by its other end to the base, a friction element adjacent the pivot of the 45 said element and the base for creating a fric-

tion between the last two recited parts, a spring operating upon the said friction element for maintaining it active, and means for varying the tension of the last recited spring.

8. A lid supporter embodying a base adapted to be secured to a fixed support, an element pivotally connected with the base, a link pivotally connected at one end to the 50 said element and at its other end to the lid, whereby when the lid is moved the parts will be moved about their respective pivots, a spring anchored at one end to the base and adjustably connected by its other end to the said element, a pair of friction creating elements encompassing the pivot between the said element and base and between which friction creating elements the first recited element is movable, and means tending normally to cause the said friction creating elements to create a friction upon the first recited element.

9. A lid supporter embodying a base adapted to be secured to a fixed support, an element pivotally connected with the base, 70 a link pivotally connected at one end to the said element and at its other end to the lid, whereby when the lid is moved the parts will be moved about their respective pivots, a spring anchored at one end to the base 75 and adjustably connected by its other end to the said element, a pair of friction creating elements encompassing the pivot between the said element and base and between which friction creating elements the first recited 80 element is movable, a spring tending normally to cause said friction creating elements to create a friction upon the first recited element, and means whereby the degree of friction may be varied.

In testimony whereof we have signed our names to this specification, on this 29th day of November, A. D. 1919.

RAYMOND T. BELL.
LOUIS MANDEL.

It is hereby certified that Letters Patent No. 1,359,953, granted November 23, 1920, upon the application of Raymond T. Bell and Louis Mandel, of Chicago, Illinois, for an improvement in "Lid-Supporters," were erroneously issued to "Ben F. Goldstein, of Chicago, Illinois," whereas said Letters Patent should have been issued to *Mandel Manufacturing Company, a Corporation of Illinois*, said corporation being assignee, by mesne assignments, of the entire interest in said invention, as shown by the records of assignments in this office; and that the said Letters Patent should be read with this correction therein that the same may conform to the record of the case in the Patent Office.

Signed and sealed this 21st day of December, A. D., 1920.

[SEAL.]

L. B. MANN,

Acting Commissioner of Patents.
